(57) **CLAIM**

The ornamental design for a portion of a squeegee, as shown and described.

DESCRIPTION

FIG. 1 is a perspective view of a squeegee in accordance with the present invention;

FIG. 2 is a front elevational view thereof;

FIG. 3 is a rear perspective view thereof; and,

FIG. 4 is a side elevational view, the opposite side being a mirror image thereof.

The broken line showing of the handle is included for the purpose of illustrating another portion of the squeegee that forms no part of the claimed design.
